UNITED STATES PATENT OFFICE.

GEORGE A. PRATT, OF COOPERSTOWN, NORTH DAKOTA.

END-GATE FOR WAGONS.

1,280,543.

Specification of Letters Patent.

Patented Oct. 1, 1918.

Application filed May 24, 1918. Serial No. 236,352.

To all whom it may concern:

Be it known that I, GEORGE A. PRATT, a citizen of the United States, residing at Cooperstown, in the county of Griggs and 5 State of North Dakota, have invented new and useful Improvements in End-Gates for Wagons, of which the following is a specification.

This invention relates to end gates for 10 wagons, and the object is to provide a device which will be securely retained in position and will prevent the material being transported in the wagon from being wasted by reason of the vibration of the end gate or the 15 displacement of the latter. The device is especially useful on wagons designed for transporting small grain, but is not limited to that use.

A further object is to provide an end gate 20 having an opening therein controlled by a slide or trap mounted in a certain novel manner hereinafter described.

In the drawings:—

Figure 1 is a view in elevation.

25 Fig. 2 is a similar view with the pivoted gate open.

Fig. 3 is a top plan view.

Fig. 4 is a detail of a fastening device for the pivoted gate.

30 The end board proper is designated 10 and is reinforced by cleats 12 near opposite ends thereof and on both sides, these cleats on one side being connected at a point midway or substantially midway of the upper 35 and lower edges of the board, by means of a strip 14 of band iron.

A cutaway portion 15 may be of substantially the form shown, this portion being closed by means of the slide 16 mounted with 40 its end portions 17 and 18 projecting under the cleats, or between the latter and the board 10. Slide 16 carries a device 25 by means of which it may be handled and thrown to an open position passing between the strip or band 14 and the board 10. The gate proper is retained in position by a rod passing lengthwise thereof and suitably secured.

45 A gate mounted as described may also be 50 used in connection with large grain tanks.

An offset member 20 affords means for mounting one end of the slide by means of a suitable pin or pivot. The handle is located just above the strip 14 when the slide is in closed position.

55 The gate 16 has mounted thereon a short bar 25, and a similar bar 26 is mounted on the end board 10, a chain 27 being secured to bar 25 and slideable thereon and having a ring 28 on the free end thereof to permit of 60 the manipulation of the chain in adjusting gate 16 to the required height. A bracket 29 on bar 26 includes a central loop 30 adapted to be engaged by the links of the chain when the latter has been properly positioned.

65 What is claimed is:

1. In a device of the class described, a gate provided with an opening, a plurality of cleats mounted on the gate near the ends thereof, portions of the cleats being spaced 70 from the surface of the gate, a strip extending between the cleats and spaced from the surface of the gate and means for closing said opening and adapted for movement between the strip and the aforesaid 75 spaced portions of the cleats, said means comprising a member higher at the central portion than at the ends, the end portions being cut away, and said member including an offset portion at one lower corner, and a 80 pin passing through the offset portion for mounting the member adjacent to the lower side of the opening in the gate, the cutaway portions permitting said member to swing angularly on its pivot without being obstructed by the cleats.

2. In a device of the class described, a gate provided with an opening therein, a member pivotally mounted at one lower corner for closing the opening, a bar extending across 90 the upper portion of the member and horizontally thereof when the member is in closed position, a retaining device secured to the gate and including a looped portion, and a chain slideable along the bar, the chain being adjustable with reference to the looped portion for holding the pivoted member in any adjusted position.

95 In testimony whereof I affix my signature.

GEORGE A. PRATT.
